UNITED STATES PATENT OFFICE.

ANDREW J. STONE AND LEA W. ROCKWELL, OF WASHINGTON, DISTRICT OF COLUMBIA,
ASSIGNORS TO THE GOVERNMENT OF THE UNITED STATES.

FUSE FOR SHELLS.

1,301,760.

Specification of Letters Patent. Patented Apr. 22, 1919.

Application filed March 27, 1918. Serial No. 225,095.

To all whom it may concern:

Be it known that we, ANDREW J. STONE and LEA W. ROCKWELL, citizens of the United States, and residents of Washington, District of Columbia, have invented certain new and useful Improvements in Fuses for Shells, of which the following is a specification.

This invention relates to fuses for projectiles, and more particularly to the impact type of fuse adapted to be located in the nose of the projectile.

One of the objects of the present invention is to provide a simple and practical fuse particularly adapted for use in connection with flat-nose, non-ricochet shells, although of course it is to be understood that it is applicable to the other types without material alteration.

Another object is to provide a fuse of the above character having relatively few parts which will be inexpensive to manufacture and assemble. A further object is to provide a fuse of the above type which will be safe to handle yet reliable and efficient in use. A further object is to provide a fuse particularly adapted for use with underwater shells to produce instantaneous explosion on impact with armor, either on direct or glancing hit.

Other objects will be in part obvious from the annexed drawings and in part indicated in connection therewith by the following analysis of this invention.

This invention accordingly consists in the features of construction, combination of parts and in the unique relations of the members and in the relative proportioning and disposition thereof; all as more completely outlined herein.

To enable others skilled in the art so fully to comprehend the underlying features thereof that they may embody the same by the numerous modifications in structure and relation contemplated by this invention, drawings depicting a preferred form have been annexed as a part of this disclosure, and in such drawings, like characters of reference denote corresponding parts throughout all the views, of which:

Figure 1 is a longitudinal central, sectional view of the fuse, and Fig. 2 is a transverse sectional view taken on the line 2—2, Fig. 1.

Referring now to the drawing in detail,

and assume that the stock is applied to the nose of the projectile, 5 denotes a fuse stock body member having a threaded forward portion 6 adapted to screw into the forward end of a projectile. The rear part of this stock member 5 is in the form of an annular flange 8, within which fits a plate 10 having a central threaded boss 11 adapted to screw into the first member 5. This plate 10 is preferably made of aluminum, or other light and inexpensive material, and is provided with a central longitudinal passage 12 terminating in a plurality of radially disposed branches 13 communicating with a chamber 14 formed thereabout and within the flanged portion 8 of the first member 5. This chamber 14 is adapted to be filled with a high explosive constituting the booster charge, which is ignited by the flash from a cap 15 located in the central part of the fuse stock.

In the front face of the stock there is provided a recess 16 holding a frusto-conical member 17 of brass or other soft metal within which is sweated a hard steel ball 18. The ball projects beyond the outer face of stock body member 5 and is so exposed that on either a direct or glancing impact the ball will be driven in to actuate the firing pin. The member 17 has an annular cut 19 away portion 19 on its outer surface to permit compression, and a central longitudinal bore 21 adapted to seat a firing pin 22. The steel ball 18, provided at the forward end of the firing pin, is firmly seated in the brass member 17 so that accidental actuation is prevented. Interposed between the rear end of the firing pin 21 and the detonating cap 15 is a safety member in the form of a pivotally mounted gate 23 held in place by means of a pin 24 and a spring 25, which gate is adapted to swing outwardly from its recess under centrifugal action during the flight of the projectile, overcoming the effect of spring 25 and placing the fuse in armed position.

From the above it will be seen that when the projectile is fired, this gate 23 swings outwardly thus leaving the cap 15 exposed whereby it may be hit by the firing pin 22 on impact of the projectile with armor. On such impact the ball 18 and firing pin 22 are driven inwardly, compressing the soft brass member 17 by reason of its cut away portions 20 thereby allowing the pin 110

21 to engage the cap 15, which in turn ignites the booster charge and explodes the projectile. The simplicity, reliability and efficiency of the present device will be obvious to those skilled in the art.

Without further analysis, the foregoing will so fully reveal the gist of this invention that others can by applying current knowledge readily adapt it for various applications without omitting certain features that, from the standpoint of the prior art, fairly constitute essential characteristics of the generic or specific aspects of this invention, and therefore such adaptations should and are intended to be comprehended within the meaning and range of equivalency of the following claims:

We claim as our invention:

1. A fuse comprising a cylindrical body member having a flange at its rear portion, a plate member defining with said flange a chamber for the booster charge, a boss integral with said plate member having its outer end threaded for engagement with said body member and provided with a detonator cavity and passages affording communication between said cavity and said chamber, a detonator in said cavity, and means for exploding said detonator.

2. A fuse comprising a cylindrical body member having a flange at its rear end, a plate member defining with said flange a chamber for the booster charge, a boss integral with said plate member having its outer end threaded for engagement with said body member and provided with a detonator cavity and passages affording communication between said cavity and said chamber, a detonator in said cavity, means for exploding said detonator, and a safety device mounted to swing in said cylindrical body member and normally interposed between said firing means and said detonator but adapted to move to armed position on the flight of the projectile.

3. A fuse comprising a body member provided with a recess, a second member of relatively soft metallic composition seated in said recess, a firing pin mounted in said second member, and a relatively hard metallic body held by said second member and projecting beyond the face thereof, and associated with said firing pin, the said hard metallic body being adapted to collapse said soft metallic member and actuate said firing pin on impact.

4. A fuse comprising a body member provided with a recess, a second member of relatively soft metallic composition seated in said recess, a firing pin mounted in said second member, and a relatively hard metallic body held by said second member and

projecting beyond the face thereof and associated with said firing pin, the said hard metallic body being adapted to compress said soft metallic member and actuate said firing pin on impact.

5. A fuse comprising a body member provided with a recess, a frusto-conical member of relatively soft metallic composition seated in said recess and having cutaway portions, a firing pin mounted in said frusto-conical member and a relatively hard metallic body held by said frusto-conical member and projecting beyond the face thereof and associated with said firing pin, said hard metallic body being adapted to collapse said frusto-conical member and actuate said firing pin on impact.

6. A fuse comprising a body member provided with a recess, a frusto-conical member of relatively soft metallic composition seated in said recess and having cutaway portions, a firing pin mounted in said frusto-conical member and a relatively hard metallic body held by said frusto-conical member and projecting beyond the face thereof and associated with said firing pin, said hard metallic body being adapted to compress said frusto-conical member and actuate said firing pin on impact.

7. In a device of the character described, a body, a detonator therein, a collapsible member mounted in said body, a firing pin positioned in said collapsible body and associated with said detonator, an exposed impact member consisting of a relatively hard metallic composition held by said collapsible member adapted to collapse said collapsible member and actuate said firing pin to explode said detonator on impact, and a safety device normally interposed between said firing pin and said detonator but adapted to move to armed position on the flight of the projectile.

8. In a device of the character described, a body, a detonator therein, a compressible member mounted in said body, a firing pin positioned in said compressible body and associated with said detonator, an exposed impact member consisting of a relatively hard metallic composition held by said compressible member adapted to compress said compressible member and actuate said firing pin to explode said detonator on impact, and a safety device normally interposed between said firing pin and said detonator but adapted to move to armed position on the flight of the projectile.

Signed at Washington, District of Columbia, this 15th day of March, 1918.

ANDREW J. STONE.
LEA W. ROCKWELL.
